UNITED STATES PATENT OFFICE.

CHRISTIAN AALBORG, OF PITTSBURGH, PENNSYLVANIA, ASSIGNOR TO WESTINGHOUSE ELECTRIC & MANUFACTURING COMPANY, A CORPORATION OF PENNSYLVANIA.

INSULATOR.

Application filed July 15, 1920. Serial No. 396,452.

My invention relates to insulating devices and particularly to insulator structures for supporting bus bars, switches and conductors.

5 One object of my invention is to provide an insulator that shall be light in weight, simple and durable in construction and effective in operation.

Another object of my invention is to provide an insulator, of a type usually comprising relatively cumbersome porcelain and cast metal parts, that shall be constructed of fibrous insulating material impregnated with a binder, and relatively-simple pressed-metal members.

Another object of my invention is to provide an insulator, and co-operating metal supporting members therefor, that shall be so formed and related as to resist forces tending to separate them and that shall permit of ready assembly and disassembly.

A further object of my invention is to provide a non-refractory insulating structure that shall be provided with protective means to increase the life thereof and to permit its effective use for outdoor service.

In certain insulating structures of the pin or pillar type adapted to support bus bars, transmission, or other line conductors and between two of which a fuse or switch arm may be adapted to extend, it has heretofore been usual to employ porcelain insulating members supported at their ends by cast metal members. Certain of these structures have been very effective in operation but their excessive weight has required that they be very strongly supported and this together with the frequent breakage has been the cause of inconvenience and expense in handling and shipping.

Fiber and other composition insulating material have not, to the best of my knowledge, been extensively employed nor considered practicable in weather-exposed service by reason of deterioration. This is particularly true where the insulators are exposed to sea air.

In practicing my invention, I provide an insulator structure in which both the insulating and metal parts are constructed of relatively-thin sheet material, thereby very greatly reducing the weight of the insulator. The insulating and conducting parts have

the forms of frustums of cones and so engage each other in telescoping clamping relation as to facilitate the assembly and disassembly of the insulator and prevent the separation of the parts.

The insulating parts are so coated with a protective enamel as to permit their use under all kinds of outdoor conditions.

In a copending application, Serial No. 394,519, filed July 7, 1920, by Frank Conrad and assigned to the Westinghouse Electric & Manufacturing Company, are disclosed the general principles of certain stress distributing members employed in the devices of my herein illustrated and described invention.

Figure 1, of the accompanying drawings, is a side view, partially in elevation and partially in section, of a high-potential switch embodying insulators constructed in accordance with my invention.

Fig. 2 is a longitudinal sectional view of a strain insulator embodying my invention.

Fig. 3 is a detail view of a sheet of material employed in the construction of an insulator embodying my invention, and

Figs. 4 and 5 are detail diagrammatic views of a mandrel and pressing members particularly adapted for the manufacture of my novel insulator.

In Fig. 1, a high-potential switch 1 comprises, in general, a base member 2, insulating pillar members 3 and 4, a pivoted blade member 5, a terminal member 6 disposed on the pillar 3 and on which the blade member 5 is pivoted, by a bolt or pin 7, and a jaw member 8 disposed on the pillar 4.

The pillar members 3 and 4 have the forms of hollow frustums of cones preferably having relatively-thin walls constructed of paper impregnated with a binder, such as a phenolic condensation product, and cut into sheets 9 of substantially segmental form in order that they may be wound successively and evenly upon a tapered mandrel 10. The paper may be coated with the binder before or during the winding operation and the sheets 9 placed successively on the mandrel 10 in substantially butt-edge relation. The wound frustum is then subjected to heat and pressure, by members 11 that conform to the shape of the mandrel 10, to compact the material while being wound and subsequent-

ly baked to harden the binder. Thus constructed, the pillar members 3 and 4 will be unaffected by wide temperature changes, moisture, weak acids and alkalis.

The base member 2 is constructed of relatively-thin sheet metal, cut and pressed to shape, having a transversely-projecting perimetral flange 12 and flanges 13 disposed on one side thereof and so formed as to constitute frustums of cones. The flanges 13 surround openings in the base member through which the pillar members 3 and 4 may be inserted, small end first, and are proportioned to snugly embrace the lower ends 15 of the pillar members. Members 14 conform to, and snugly fit, the inner surfaces of the pillar members at the bases of the latter and are provided with apertured transversely-projecting flanges or lugs 15 that may be secured to the base member 2 by means of screws 16.

Similarly, at the outer ends of the pillar members 3 and 4, pressed metal members 17 and 18 of substantially cup-shape conform to, and snugly fit, the outer and inner surfaces, respectively, of the members 3 and 4. Screws 19, or other suitable means, may be employed to secure the terminal members 6 and 8 to their respectively-adjacent sets of 30 the members 17 and 18 and to hold the latter in clamping relation to the pillar members.

The members 14 are provided with integral dome portions 20 extending into the insulating members 3 and 4, beyond the flanges 35 13 and the members 18 are provided with separable dome members 21, secured thereto by screws 22, that similarly extend into the insulating members 3 and 4 to better distribute the electrostatic stresses, as explained 40 in the above mentioned copending application.

In an insulator or other device constructed as above described, the members 3 and 4 cannot be displaced outwardly from the flanges 45 13 nor the members 18 displaced outwardly from the members 3 and 4, because any forces, other than forces greater than the tensile strengths of the materials tending to displace the parts, serve only to more securely bind the co-operating parts together.

Obviously, by employing slightly modified parts at the outer ends of the members 3 and 4, or by employing one only of the pillar members, the device may readily be adapted 55 as a support for bus-bars, transmission-line or other conductors.

In Fig. 2, a similar structure adapted as a strain insulator is shown. At the smaller end of an insulating member 3, members 17 60 and 18 are secured in position by a bolt 23 to which an eye member 24 is attached. At the larger end of the member 3, a member 13a co-operates with a member 14 to clamp the insulating member 3. A disk 25, supporting an eye member 26, engages the outer members 65 and longitudinally relatively mov-

perimeter of the member 14 and is secured in position by screws 16 that also hold the members 13a and 14 in place.

In constructing the insulating members 3, the sheets 9 are successively wound on the 70 mandrel 10, after which the members 3 are subjected to heat. During the time that one of the members 3 is being heated, the pressing members 11 are moved radially with respect to the mandrel 10 to compress the 75 member 3. A coating 27, preferably of enamel, is applied to the members 3 to protect them against adverse influences such as flashovers and the effects of weather.

While I have shown and described particular forms of my invention, changes may be effected therein without departing from the spirit and scope thereof, as set forth in the appended claims.

I claim as my invention:

1. In an insulator, the combination with an insulating member embodying a tubular terminal portion having substantially frusto-conical inner and outer surfaces, of a terminal device comprising clamping members 90 that by longitudinal relative movement laterally clamp said inner and outer surfaces and means for connecting said clamping members and longitudinally moving the same to thus clamp said terminal portion.

2. In an insulator, the combination with an insulating member embodying a hollow terminal portion having inner and outer longitudinal surfaces sloping relative to the longitudinal axis of the terminal portion, 100 of a terminal device comprising clamping portions that, by longitudinal relative movement, laterally clamp said sloping-surface terminal portion between them and means for connecting said clamping portions and 105 longitudinally relatively moving the same to thus clamp said terminal portion.

3. In an insulator, the combination with an insulating structure embodying a substantially tubular terminal portion having laterally-opposite inner and outer longitudinal side surfaces one of which slopes longitudinally, of a terminal device comprising clamping members that, by longitudinal relative movement, laterally clamp said 115 opposite-surface terminal portion between them, and means cooperating between said clamping members for longitudinally relatively moving the same to thus clamp said terminal portion.

4. In an insulator, the combination with an insulating member having substantially frusto-conical inner and outer surfaces, of a terminal device comprising longitudinally relatively movable clamping members having substantially frusto-conical tubular portions substantially conforming to said surfaces inside and outside said insulating member, and means for connecting said clamping 125 members and longitudinally relatively mov-

ing the same to clamp the tubular portions thereof against the insulating member.

5. In an insulator, the combination with an insulating member embodying a tubular 5 terminal portion having substantially frusto-conical inner and outer surfaces, of a terminal device comprising longitudinally relatively movable clamping members having substantially frusto-conical tubular clamp- 10 ing portions conforming to, and cooperating with, said inner and outer surfaces and laterally-extending portions, and means co-operating between said laterally-extending portions for longitudinally relatively mov- 15 ing said clamping members to clamp said tubular terminal portion of the insulating member between said clamping portions.
6. In an insulator, the combination with a tubular insulating member having por- 20 tions including substantially frusto-conical inner and outer surfaces, of a terminal de-

vice for each end thereof comprising clamping members that, by longitudinal relative movement, laterally clamp said portions between them and means for connecting said 25 clamping members and longitudinally moving the same to thus clamp the insulating member.

7. In an insulator, the combination with an insulating structure having laterally- 30 opposite longitudinal surfaces, one of which slopes longitudinally, of a terminal device comprising clamping members that, by longitudinal relative movement, laterally clamp said surfaces between them, and 35 means cooperating between said clamping members for connecting and longitudinally relatively moving the same to thus clamp said insulating structure.

In testimony whereof, I have hereunto sub- 40 scribed my name this 9th day of July, 1920.

CHRISTIAN AALBORG.
